INTERNAL-COMBUSTION MOTOR.

1,261,097.

Specification of Letters Patent.

Patented Apr. 2, 1918.

Application filed January 29, 1917. Serial No. 145,073.

To all whom it may concern:

Be it known that I, FRANK E. BLANCHARD, a citizen of the United States of America, residing at Toledo, Lucas county, Ohio, have 5 invented new and useful Internal-Combustion Motors, of which the following is a specification.

This invention relates to port control mechanism.

10 This invention has utility when incorporated in connection with a piston reciprocable in a cylinder, especially in internal combustion motors.

Referring to the drawings:

15 Figure 1 is a side elevation, with parts broken away, of an embodiment of the invention in an internal combustion motor;

Fig. 2 is a section on the line II—II, Fig. 1;

20 Fig. 3 is an enlarged section on the line III—III, Fig. 1; and

Fig. 4 is a section partially on the line IV—IV, Fig. 3.

The housing 1 is water-jacketed to inclose 25 the cylinders 2 provided with an intake port 3 and an outlet or exhaust port 4 for each cylinder. Reciprocable in each cylinder is a piston 5 having the lateral gridded port 6, the way from which extends out of the end

30 of the piston 5 to open into the chamber of the cylinder. Centrally connected to each piston by a spherical bearing 7 is a connecting rod 8 extending to the crank shaft 9. In the operation of this device as an in- 35

ternal combustion motor, the reciprocation of the piston 5 in this cylinder will operate through the connecting rod to rotate the shaft 9 from which rotatable means, power may be transmitted to perform work.

40 Mounted on the crank shaft 9 is the sprocket wheel 10 connected by the sprocket chain 11 to the sprocket wheel 12 for driving the valve shaft 13 at the same angular velocity as the shaft 9. This shaft 13 carries a

45 spiral gear 14 adjacent each cylinder to mesh with a spiral gear or toothed section 15 on each auxiliary rotatable non-reciprocating cylinder 16, axially aligned with each main cylinder 2 for two to one speed reduction 50 in the rotation of the cylinders 16.

The piston 5 has annular packing 17 adjacent its free end or remote from the crank shaft and has the annular packing 18 at the

opposite end. Upon opposite sides of the port 6, the cylinder 5 is provided with longitudinal packing or wipers 19 (Fig. 2). There is, accordingly, effective packing of the lateral port regions of the piston 5 as to the lateral ports of the fixed cylinder 2.

The piston 5 beyond the packing 18 has the guide means or lugs 20 in a peripheral annular series on the side thereof remote from the port 6. These guides 20 register to reciprocate in the relatively interfitting guide ways 21 extending longitudinally of 65 the auxiliary or second cylinder 16. Accordingly, the rotation of the shaft 9 is transmitted to rotate at one-half its speed the cylinder 16 and thereby give the piston one complete rotation in two of its reciprocations.

In the throw of the piston 5 away from the shaft 9, the lugs 20 travel in the guides 21 toward the end thereof. A lubricant supply, preferably force feed, through the pipe 75 22, conveys fluid into the housing 1 surrounding the cylinder 16. This cylinder 16 has spiral ways 23 for conducting this fluid in thoroughly lubricating its rotation. These ways 23 terminate in a top annular groove 80 24 into which ports 25 lead from the ends of the guide ways 21. This serves not only to lubricate the piston in its reciprocation but operates as a fluid cushion to absorb concussion in the travel of the piston 5 to have 85 its lugs 20 approach the ends of the ways 21.

The device of this disclosure is compact in features of assembly permitting effective water-jacketing of the heat regions. The actuation of the piston for rotation is by 90 a device of simple structure with few parts to complicate and these parts disposed for permitting close assembly of the cylinders as to each other with maximum clearance for the connecting rod. This means a most 95 advantageous stroke bore ratio. Considerable range is permissible in the disposing of the pair of ports for each cylinder as to the pair of ports for the adjacent cylinder, the disclosure in Fig. 2 being in pairs with 100 the auxiliary cylinders or sleeves 16 rotating toward each other as shown by the arrows. This permits a range for proportioning the manifold in various groupings for clearance as well as passage lengths giving 105 the structure considerably flexibility in de-

sign for such utilities as may be desirable. These points are of peculiar value in motor vehicle constructions.

In disposing the rotatable port control means or auxiliary cylinders 16 adjacent such means in the next cylinder of the motor and oppositely driving these cylinders from the toothed members or spiral gears 14, the toothed portions 15 of the adjacent sleeve 16 may be in mesh thereby permitting a most close grouping of the cylinders. Furthermore, the opposite pitching of the gears 14 tends to neutralize the thrusts of these auxiliary cylinder driving loads in the shaft 13.

The effective driving of these port control sleeves may be in gang from a single pinion 14 say for each pair of cylinders in a four, or each three in a six, or other desired multiple grouping.

What is claimed and it is desired to secure by Letters Patent is:

1. A cylinder provided with lateral port means, a ported piston in said cylinder, rotatable means connected to said piston, and means for rotating said piston from said rotatable means including an auxiliary rotatable cylinder having a guide of an axial extent in excess of the piston travel, said piston being provided with a guide of less extent than the piston travel coating with

the auxiliary cylinder guide for simultaneous rotation of the auxiliary cylinder and piston permitting relative reciprocation of the piston.

35

2. An internal combustion motor embodying a cylinder having a pair of ports, a relatively reciprocable piston in said cylinder, said piston having a single port, and a non-reciprocating cylindrical member for rotating the piston, said cylindrical member having its cylindrical axial extent as great as the piston travel reciprocations.

40

3. A reciprocable piston provided with a peripheral series of lugs adjacent one end, a cylinder in which said piston is rotatable, a second cylinder rotatable with the piston and having ways for the piston lugs, said ways terminating in ported pockets to provide fluid cushioning means for the piston.

45

4. A motor embodying a plurality of cylinders, rotatable pistons in said cylinders, toothed driving sleeves having spline coaction with the pistons for rotating said pistons, and within the axial extent of one of which sleeves one end of the piston is reciprocable, the teeth of said driving sleeves on a pair of adjacent cylinders meshing with each other.

50

In witness whereof I affix my signature. 60

FRANK E. BLANCHARD.
